SPECTACLE FRAME

Albert L. Anderson and Leslie W. Myers, Minneapolis, Minn., assignors to Precision-Cosmet Company, Inc., Minneapolis, Minn., a corporation of Minnesota

Application May 12, 1948, Serial No. 146,315

Term of patent 14 years

(Cl. D57—1)

To all whom it may concern:

Be it known that we, Albert L. Anderson and Leslie W. Myers, both citizens of the United States and residing in the city of Minneapolis, Hennepin County, Minnesota, have invented a new, original, and ornamental Design for a Spectacle Frame, of which the following is a specification, reference being made to the accompanying drawing, forming a part thereof, wherein:

Figure 1 is a perspective view of a spectacle frame, showing our new design;

Figure 2 is a front elevational view thereof;

Figure 3 is a side view thereof;

Figure 4 is a plan view thereof with one of the temples swung to a collapsed position;

Figure 5 is a typical sectional view taken on the line 5—5 of Fig. 3; and

Figure 6 is an enlarged typical plan view of a portion of the ornamented surface thereof.

The surface ornamentation of the design comprises a multiplicity of well defined, contiguous, concave facets of irregular shape, said facets being joined with adjacent facets along sharply defined edges.

We claim:

The ornamental design for a spectacle frame, as shown and described.

ALBERT L. ANDERSON.
